UNITED STATES PATENT OFFICE.

WILLIAM J. BROWN, OF PITTSBURGH, PENNSYLVANIA.

WALL-PAPER-REMOVING MACHINE.

1,313,462.

Specification of Letters Patent.

Patented Aug. 19, 1919.

Application filed March 26, 1918, Serial No. 224,864. Renewed March 12, 1919. Serial No. 282,193.

To all whom it may concern:

Be it known that I, WILLIAM J. BROWN, a citizen of the United States of America, residing at Pittsburgh, in the county of Allegheny and State of Pennsylvania, have invented certain new and useful Improvements in Wall - Paper - Removing Machines, of which the following is a specification.

This invention relates to wall paper removing machines, and has for its object to provide a machine of such class, in a manner as hereinafter set forth, which is capable of being shifted over a wall for splitting the paper thereon and then scraping it therefrom, thereby cleaning the wall of the paper.

A further object of the invention is to provide a wall paper removing machine, in a manner as hereinafter set forth, having a scraping knife and a guide associated with said knife, said guide preventing the knife from entering deeply into the plaster-wall, during the operation of removing the paper off the latter.

Further objects of the invention are to provide a wall paper removing machine which is simple in its construction and arrangement, strong, durable, portable, efficient and convenient in its use, readily set up and comparatively inexpensive to manufacture.

With the foregoing and other objects in view this invention consists of the novel construction, combination and arrangement of parts, hereinafter more specifically described and illustrated in the accompanying drawings, wherein is shown an embodiment of the invention; but it is to be understood that changes, variations and modifications can be resorted to which come within the scope of the claims hereunto appended.

In the drawings wherein like reference characters denote corresponding parts throughout the several views:

Figure 1 is a longitudinal sectional view on line I—I, Fig. 2, of a wall paper removing machine in accordance with this invention.

Fig. 2 is a sectional plan, line II—II, Fig. 1.

Fig. 3, is a side elevation of the machine.

Fig. 4 a front view.

Fig. 5 an elevation of the scraping knife.

Fig. 6 a perspective view of one of the splitting knives.

Referring to the drawings in detail the machine comprises a frame consisting of a pair of side members, 1, 2, a bottom plate 3,

integral with and arranged intermediate of the ends of the side members 1, 2. End portions 4, 5, of greater height than the side members, are formed integral with these latter members.

The side members 1, 2, near their rear ends, are provided with inwardly extending bearings 6, 7, for a transverse axle 8, carrying a pair of wheels 9, which are arranged within the frame and depend slightly below the bottom thereof. The axle 8, has a bevel gear 10.

Supported by the plate 3, is an electric motor 11, the shaft 12, of which projects rearwardly and forwardly therefrom. The rear end of the shaft 12, carries a bevel gear 13, which meshes with the bevel gear 10, the latter being of materially greater diameter than the bevel gear 13. The reference character 14, denotes leading-in-wires for the motor 11.

The plate 3, forwardly of the motor 11, is formed with a hollow standard 15, which provides a bearing for the shaft 16, projecting from the hub 17, of a bevel gear wheel 18. The hub 17, is seated upon the standard 15. The forward end of the shaft 12, is provided with a bevel gear 19, which meshes with a bevel gear 18.

The end member 5, at its lower end has an inclined slot 20, and above said slot is formed with a pair of openings 21. The rear face of the end member 5, at the openings 21, is reinforced by bosses 22.

Reciprocating through the slot 20 is an inclined scraping knife 23, which is adjustably connected by the said screws 24, and slots 25, to a carrier 26, which is fixed to a pair of reciprocating guide bars 25^a, operating through the openings 21, and also through the apertured upper ends of fixed standards 25^b, which are secured to the bottom plate 3, at each side of the gear 18.

The gear has a pin 26^a, to which is pivotally connected a lever arm 27, the latter being pivotally connected to the carrier 26, as at 28.

Adjustably mounted upon the end member 5, as well as having its lower end projecting forwardly of the knife 23, is a yoke shaped governing member 29, the latter being adjustably connected to the end member 5, as at 30. The lower portion of the governing member 29, which projects forwardly from the end member 5, consists of a pair of guide bars 31, 32, which are spaced apart to

provide a discharge slot for the paper which has been removed by the knife 23. The opposed walls of the slot 33, are reversely curved with respect to each other, as at 5 34, 35, and a part of said slot 33, is always positioned forwardly of the extreme limit of the outward stroke of the knife 23. The bar 32, is arranged in advance of the knife 23.

10 Connected to each end of the bar 32, is a splitting knife 35', which is slotted as at 36, and the latter in connection with the screw 37, provides means for adjustably connecting the splitting knife 35', in position. The splitting knife 35', in connection with the bar 32, travels forwardly of the scraping knife 23, and will prevent the latter from entering the plaster wall too deeply, when traveling over an uneven wall 15 surface, under such conditions governing the scraping stroke of the knife 23.

15 The motor 11, is not only employed for propelling the machine over the wall, but also for operating the knife.

20 Hinged to the member 2, as at 38, is a lid or cover 39, which when closed is seated upon ribs 40, projecting inwardly from the end members 4, 5. The lid or cover 39, is detachably connected as at 41, to the side 25 member 1.

25 A flexible handle 42, is provided and is secured at one end as at 43, to the cover 39, and at its other end as at 44, to the side member 2. The leading in wires 14, extend 30 outwardly through the end member 4.

30 The knives 35', are employed for splitting the paper prior to the scraping of the same off the wall by the knife 23, and under such conditions the paper removing operation will be expedited. The paper scraped from the wall by the knife 23, is caused to 35 pass up through the slot 33, as illustrated by Fig. 1.

35 A suitable switch may be employed, for 40 opening and closing the electrical circuit for controlling the operation of the motor 11.

45 What I claim is:

1. A wall paper removing machine comprising a reciprocatory inclined scraping knife, a governing member controlling the depth of the cut of said knife during the operation thereof, and splitting knives carried by said governing member in advance of the 50 scraping knife, said governing member having a discharge slot for the removed paper, said slot arranged rearwardly of the splitting knives.

2. A wall paper removing machine comprising a reciprocatory inclined scraping knife, a governing member controlling the depth of the cut of said knife during the operation thereof, and splitting knives carried by said governing member in advance 55 of the scraping knife, a frame, and guide

bars for said scraping knife extending through one end of the frame.

3. A wall paper removing machine comprising a reciprocatory inclined scraping knife, a governing member controlling the 70 depth of the cut of said knife during the operation thereof, and splitting knives carried by said governing member in advance of the scraping knife, said governing member having a discharge slot for the removed paper, said slot arranged rearwardly of the splitting knives, a frame, and guide bars for said scraping knife extending through one end of the frame. 75

4. A wall paper removing machine comprising a reciprocatory inclined scraping knife, a governing member controlling the depth of the cut of said knife during the 80 operation thereof, and splitting knives carried by said governing member in advance of the scraping knife, a frame for supporting said knife and member, a motor arranged within the frame, an operative connection between said scraping knife and said motor for reciprocating the knife, propelling wheels for the frame and an operative connection between said wheels and said motor for driving the wheels. 85

5. A wall paper removing machine comprising a reciprocatory inclined scraping 90 knife, a governing member controlling the depth of the cut of said knife during the operation thereof, and splitting knives carried by said governing member in advance of the scraping knife, said governing member having a discharge slot for the removed paper, said slot arranged rearwardly of the splitting knives, a frame for supporting said knife and member, a motor arranged within the frame, an operative connection between 95 said scraping knife and said motor for reciprocating the knife, propelling wheels for the frame and an operative connection between said wheels and said motor for driving the wheels. 100

6. A wall paper removing machine comprising a reciprocatory inclined scraping knife, a governing member controlling the depth of the cut of said knife during the 105 operation thereof, and splitting knives carried by said governing member in advance of the scraping knife, a frame for supporting said knife and member, a motor arranged within the frame, an operative connection between said scraping knife and said motor for reciprocating the knife, propelling wheels for the frame and an operative connection between 110 said wheels and said motor for driving the wheels. 115

7. A wall paper removing machine comprising a reciprocatory inclined scraping knife, a governing member controlling the depth of the cut of said knife during the 120 125

operation thereof, and splitting knives carried by said governing member in advance of the scraping knife, said governing member having a discharge slot for the removed paper, said slot arranged rearwardly of the splitting knives, a frame for supporting said knife and member, a motor arranged within the frame, an operative connection between said scraping knife and said motor for reciprocating the knife, propelling wheels for the frame and an operative connection between said wheels and said motor for driving the wheels, and guide bars for said scraping knife, said bars extending through one end of said frame.

8. A wall paper removing machine comprising a reciprocatory inclined scraping knife, a governing member controlling the depth of the cut of said knife during the operation thereof, and splitting knives carried by said governing member in advance of the scraping knife, a frame for supporting said knife and member, a motor arranged within the frame, an operative connection between said scraping knife and said motor for reciprocating the knife, propelling wheels for the frame and an operative connection between said wheels and said motor for driving the wheels, and guide bars for said scraping knife, said bars extending through one end of said frame, and means for adjusting said governing member.

9. A wall paper removing machine comprising a reciprocatory inclined scraping knife, a governing member controlling the depth of the cut of said knife during the

operation thereof, and splitting knives carried by said governing member in advance of the scraping knife, said governing member having a discharge slot for the removed paper, said slot arranged rearwardly of the splitting knives, a frame for supporting said knife and member, a motor arranged within the frame, an operative connection between said scraping knife and said motor for reciprocating the knife, propelling wheels for the frame and an operative connection between said wheels and said motor for driving the wheels, and guide bars for said scraping knife, said bars extending through one end of said frame, and means for adjusting said governing member.

10. A wall paper removing machine comprising a reciprocatory scraping knife, a governing member projecting forwardly of said knife, and having a paper discharge slot, and splitting knives connected to the governing member and arranged forwardly of the scraping knife.

11. A wall paper removing machine comprising a reciprocatory scraping knife, a governing member projecting forwardly of said knife, and having a paper discharge slot, and splitting knives connected to the governing member and arranged forwardly of the scraping knife, and means for adjusting said governing member.

In testimony whereof I affix my signature in the presence of two witnesses.

WILLIAM J. BROWN.
